Lavern Reynolds,
By Rich'd A. Manning, Atty.

UNITED STATES PATENT OFFICE.

LAVERN REYNOLDS, OF KANSAS CITY, MISSOURI.

IRONING-BOARD ATTACHMENT.

SPECIFICATION forming part of Letters Patent No. 449,172, dated March 31, 1891.

Application filed August 2, 1890. Serial No. 360,755. (No model.)

To all whom it may concern:

Be it known that I, LAVERN REYNOLDS, a citizen of the United States, residing at Kansas City, in the county of Jackson and State 5 of Missouri, have invented certain new and useful Improvements in Ironing-Board Attachments; and I do hereby declare that the following is a full, clear, and exact description of the invention, such as will enable others 10 skilled in the art to which it appertains to make and use the same, reference being had to the accompanying drawings, forming a part of this specification.

The primary object of my invention is to 15 afford the means for retaining the original shape of the neck-yoke and neck of a shirt or similar article of personal wear during the operation of ironing upon the ironing-board, and thereby prevent the spreading of the 20 yoke and neck of the garment during such process; and it consists in the novel construction and combination of parts, which will first be fully described, and specifically pointed out in the claims.

25 In the drawings, Figure 1 is a view in perspective of my improved yoke-securing lever removed from the ironing-board. Fig. 2 is a plan view showing an end portion of the ironing-board with the depression to receive the 30 neck-yoke band and the securing-lever, also showing the neck-yoke portion of a shirtbosom upon the ironing-board and the yoke-band secured by the jointed lever. Fig. 3 is an end view of the ironing-board as seen in 35 Fig. 2. Fig. 4 is a broken detail in perspective of the shoe and the flanged end portion of the lever, showing the hinge by means of which the shoe and lever are connected.

In my invention, A represents an ironing- 40 board, which is of the ordinary width of the bosom of the garment to be ironed and of a suitable thickness. In the upper surface and extending from one end of said board the desired distance in the direction of the other 45 end is made a depression a, the sides a' a' of which depression at the end of said board A are each equally distant from the respective longitudinal edges of said board, to which it is adjacent and at a suitable distance apart 50 corresponding to the width of the neck-opening between the separate portions of the neck-yoke of the shirt or garment to be ironed. From the end of said board and from two op-

posite centers at said end the sides a' a' of said depression a are made to describe in the 55 direction of the other end of said board meeting curves intersecting in one direction, and the lines of said curves are made equal to the lengths of the neck-yoke band on the separate portions of the neck-yoke of the shirt or 60 garment. The sides a' a' of the depression a are slightly inclined in an outward direction, for the purpose hereinafter described.

In the depression a is placed the lever B, which consists of two longitudinal bars b b', 65 both of which are narrow in width and comparatively short in length. Upon the side and near the end of one of the bars b is cast a ring b², a flanged portion b³ of which ring extends a short distance beyond the end of 70 said bar b in line with the side portion of the bar to which the said ring is attached, forming a stop or shoulder.

To the end portion of the bar b provided with the ring b³ is hinged one end of the 75 other bar b', the pivot b⁴ of which hinge extends in a vertical direction through the separate jointed portion of said bars and in connection with the shoulder b³ forming a stop-hinge. The other ends of the respective bars 80 b b' extend in the transverse direction of the ironing-board A in the direction of and nearly to the respective sides a' a' of the depression a in said board and are increased by the flanges b⁵ b⁵ on either side a short distance in 85 width, and to said ends of each bar b b' is hinged the rocking blocks or shoes b⁶ b⁶. Each one of the blocks or shoes b⁶ is of the corresponding thickness of the bars b b' and of an increased length to the said end portion 90 of the bars having the flanges b⁵ and is curved upon its outer surface. The inner surface of the shoe is connected horizontally with the end portion of the bar b by means of a hinge-joint b⁷, the pivot b⁸ of which extends in a 95 vertical line of direction through the respective ends of the bars b b' and close to the extremities of the said ends of said bars, so as to leave a space b⁹ between the end of the bar and the shoe and form a rocking joint, so that 100 the contact of the shoe is with the flanges b⁵. In line with the curved outer surface of the shoe b⁶ and from the portion of said shoe in line with the side of the bars b b' having the ring b² is extended a short distance a curved 105 thimble-plate b¹⁰, on the extended end portion

of which plate on the side in the direction of the respective bars b b' is rigidly attached a thimble b^{12} , the perforation in which is in a vertical direction. The bars b b' are first placed in line with each other, so that the shoes b^6 b^6 nearly touch the sides a' a' of the depression a in the board A, and through said board in a vertical line with the perforation in the thimble b^{12} are made the perforations a^2 a^2 . Through the said thimble b^{12} and the perforations a^2 are inserted the bolts a^3 , which are provided with heads a^4 at one end and screw-threaded and provided with the securing-nuts a^5 at the other. Upon the outer curved surface of each shoe b^6 , opposite the sides a' a' of the depression a in the board A, is attached in a suitable manner a yielding pad C, which is composed of felt, wool, or any other suitable material.

In the operation of my invention let D represent the shirt-bosom to be ironed, d d the neck-yokes, and d' the neck-yoke band. The shirt-bosom is placed in position so as to bring the neckband in line with the edges a' a' of the depression a in the board A, and said band is pressed downward within the depression a of the ironing-board and close against the sides a' a' of the said depression, the inclination of which side is sufficient to permit the close engagement of the neckband therewith without stretching. The lever B, which is normally in the position seen in dotted lines, Fig. 2, is seized by the hand at the point b^2 and the bars forced into a position in line with each other, as seen in full lines, Fig. 2, the shoulder b^3 limiting the extended position of the lever, after which the garment is drawn into conformity with the other portion of the ironing-board in readiness to be ironed. In this movement the shoes b^6 turn upon the pivots or bolts a^3 , and the flanges b^5 upon the side of the bars are caused to bear and press upon the shoes b^6 , and the pad C, which prevents the band from being drawn over the otherwise smooth surface of the shoes, is wedged against the said band d' , and the surface of the bosom is kept smooth and prevented from creasing. The position of the lever B can be readily changed and screws used in place of the bolts, the ordinary position, however, being preferred, in which the lever will exert an equal pressure upon the neckband at each side of the neckband opening.

The bars b b' , with the rocking shoes, may be used in other combinations than in the exact combination described.

Having fully described my invention, what I now claim as new, and desire to secure by Letters Patent, is—

1. A lever composed of separate longitudinal parts or bars having the adjacent ends of the separate bars hinged together and the other ends provided with rocking shoes hinged thereto, substantially as and for the purpose described.

2. A lever composed of separate longitudinal parts or bars having a stop-hinge connected with and between the adjacent end portions of the separate bars and the other or outer end portions of each of said bars provided with a rocking shoe hinged thereto, and a pad upon the outer surface of said shoe, substantially as described.

3. A lever composed of separate longitudinal parts or bars having the adjacent ends of the separate bars hinged together, and laterally-extended flanges upon the other ends of said bars, rocking shoes hinged to said flanged end portions of said bars, and a thimble-plate and thimble connected with said shoes, substantially as and for the purpose described.

4. In an ironing-board having a depression in its upper surface, and sides to said depression adapted to receive the neckband of a garment, the combination of a hinge-jointed lever extending from one to the other side of such depression having hinged rocking shoes to clamp the neckband, substantially in the manner described.

5. In an ironing-board having a depression in its upper surface and sides to said depression, the combination of a jointed lever composed of separate longitudinal parts or bars having a stop-hinge connected with and between the adjacent ends of the separate bars and the other ends of said bars provided with rocking shoes, substantially as and for the purpose described.

6. In an ironing-board having a depression in its upper surface and sides to said depression adapted to receive the neckband of a garment, the combination of a jointed lever composed of separate longitudinal parts or bars having a stop-hinge connected with and between the adjacent ends of the separate bars and flanges upon the sides of the other extended ends of said bars, and rocking blocks or shoes hinged to said extended ends of said bars provided with yielding pads, substantially as and for the purpose described.

7. In an ironing-board having a depression in its upper surface and sides to said depression adapted to receive the neckband of a garment, the combination of a jointed lever composed of separate longitudinal parts or bars having a stop-hinge connected with and between the adjacent ends of the separate bars and flanges upon the sides of the other extended ends of said bars, rocking shoes hinged to said extended flanged ends of said bars having a thimble-plate and thimble pivotally connected with said ironing-board, and a pad upon the outer surface of said segments and a ring connected with one of said bars near said stop-hinge, substantially as and for the purpose described.
